UNITED STATES PATENT OFFICE.

FREDERICK GIRTANNER, OF ST. LOUIS, MISSOURI.

WATER-HEATER.

1,110,484.

Specification of Letters Patent.

Patented Sept. 15, 1914.

Application filed April 10, 1912. Serial No. 689,860.

To all whom it may concern:

Be it known that I, FREDERICK GIRTANNER, a citizen of the United States, residing at St. Louis, Missouri, have invented a certain new and useful Water-Heater, of which the following is such a full, clear, and exact description as will enable any one skilled in the art to which it appertains to make and use the same, reference being had to the accompanying drawings, forming part of this specification.

My invention relates to water heaters, and, more particularly, to that class of water heaters which are portable and which are adapted to be immersed in the water to be heated.

In the accompanying drawings, which illustrate one form of water heater made in accordance with my invention, Figure 1 is a vertical section; Fig. 2 is a vertical section on the line 2—2 of Fig. 3; Fig. 3 is a side elevation, some of the parts being shown in section; Fig. 4 is a perspective view, showing the upper end of the burner tube; Fig. 5 is a top plan view, some of the parts being broken away; Fig. 6 is a section through the burner tube; Fig. 7 is a perspective view, showing the lower end of the burner tube.

Like marks of reference refer to similar parts in the several views of the drawings.

10 represents the body of the heater within which is the combustion chamber; passing laterally through this combustion chamber are a pair of small water tubes 11 and 35 a pair of large water tubes 12. Contained within the water tubes 12 are weights 13 for holding the heater in its submerged position in the water; these weights 13 are provided with lugs 14 which space them 40 from the tubes 12 so as to leave a substantially uniform water space between the two parts. An outer burner containing tube 15 is secured to the top of the body 10 by a water tight joint. Within this outer burner 45 containing tube 15 is an inner burner tube 16, best shown in Fig. 6; the upper end of this inner burner tube is provided with a mixer 17 of any suitable form, to which is attached a flexible gas tube 18. The lower 50 end of the burner tube 16 is provided with a burner cap 19 which is provided on its lower end with openings 20 for the discharge of the gas, and at opposite sides with openings 21. The tube 16 is removable from 55 the tube 15 and in order that when the tube 16 is inserted in the tube 15, the openings 21

may face in the proper direction, the inner pipe 16 is provided with a projection 22 and the outer pipe 15 with a slot 23, as best shown in Fig. 4. Burner slots 21 are arranged to throw the flame to the forward and rear parts of the combustion chamber, but not to throw the flame laterally. In order to supply the combustion chamber with air, I place at each side of the burner tube 15, inlet tubes 25, best shown in Fig. 2; these tubes, as will be seen from this figure, pass down through the top of the combustion chamber to a point adjacent to the bottom of the combustion chamber; the tubes 70 are open both at the top and bottom and taper slightly toward their lower ends, as clearly shown in the drawings. I have found that the tapering of the tubes 25, together with the fact that they extend slightly 75 below the burner 19, insures the proper flow of air through the heater such as can not be obtained without the use of these features. In order that the products of combustion may escape from the combustion chamber 80 10, this chamber communicates at each end with a passage 26 terminating in an upwardly projecting flue 27; this flue 27 is arranged adjacent to the inlet flue 25; 28 designates handles which are carried by 85 brackets 29. It is often desirable to carry away the products of combustion with heaters of this class and, in order to accomplish this, I provide a hood 30 which covers and surrounds outlet flue 27 as shown in Figs. 90 1 and 3; this hood 30 is preferably supported by means of the brackets 29 which carry the handles 28; the hood 30 is provided at one side with a slot 31 for the passage of the gas tube 18, as best shown in Fig. 3. 95

The operation of my device is as follows: The body of the heater is submerged in the water to be heated. The water should cover both the main body of the heater and the upper passages 26 to the depth of several 100 inches. In order to light the burner, the hood 30 is first removed and then the inner burner tube 16 is withdrawn from the outer burner containing tube 15 and the gas, after being turned on, is lighted at the cap 19. The 105 inner burner tube 16 is then inserted within the outer burner containing tube 15, and, as has been previously described, the projection 22 on the inner burner tube 16 will fit in the slot 23 on the outer burner tube 15, and thus cause the burner slots 21 to throw the flames to each end of the combus-

tion chamber but to prevent them from being thrown against the inlet tubes 25; in this way, a proper circulation of air in the combustion chamber is insured. After the 5 burner has been lighted, the conical hood 30 may be replaced to carry away the products of combustion at any suitable point. The body of the heater, owing to its form and the use of the water tubes 11 and 12, 10 presents a large heating surface to the water and thus insures rapidity of action of the heater.

Having fully described my invention, what I claim as new and desire to secure by 15 Letters Patent of the United States is:

1. In a water heater, the combination with a combustion chamber adapted to be submerged in the water to be heated, of water tubes passing laterally through said combustion chamber, weights for overcoming the buoyancy of the heater, said weights being arranged within said water tubes, so as to allow the circulation of the water, a burner for said combustion chamber, and 25 inlet and outlet passages for said chamber.

2. In a water heater, the combination with a combustion chamber adapted to be submerged in the water to be heated, of water tubes passing laterally through said combustion chamber, weights in said water tubes, said weights being provided with lugs for spacing the same from the walls of the tubes, and a burner for said combustion chamber.

3. In a water heater, the combination with a combustion chamber adapted to be submerged in the water to be heated, of inlet and outlet passages for said combustion chamber, a burner, a supply pipe for said 30 burner, and a removable hood for the outlet of said combustion chamber, said hood be-

ing slotted for the passage of the supply pipe.

4. In a water heater, the combination of 45 a combustion chamber adapted to be submerged in the water to be heated, a tube communicating with the central portion of the combustion chamber forming a passage for the insertion and removal of the 50 burner, a burner supported in the central portion of the combustion chamber and removable through the said tube, a tapering air supply tube communicating with the combustion chamber at a point adjacent to 55 the burner, and two outlet conduits for the combustion chamber communicating with the said chamber on opposite sides of the burner and at points removed in a horizontal 60 direction from the burner.

5. In a water heater, the combination of a horizontally extending box-like combustion chamber, a tube communicating with said chamber at the center of its upper portion and forming a passage for the insertion 65 and removal of the burner, a burner supported in the central portion of the combustion chamber and removable through said tube, a tapering air supply tube communicating with the combustion chamber at a 70 point adjacent to the burner, two outlet conduits communicating with the combustion chamber at points removed in a horizontal direction from the burner, and water tubes extending through the combustion chamber. 75

In testimony whereof, I have hereunto set my hand and affixed my seal in the presence of the two subscribing witnesses.
